UNITED STATES PATENT OFFICE.

WILLIAM F. BOCKHOFF, OF RICHMOND, INDIANA, ASSIGNOR TO NATIONAL AUTOMATIC TOOL COMPANY, OF RICHMOND, INDIANA, A CORPORATION OF INDIANA.

SIGHT-FEED OILER.

1,150,988.

Specification of Letters Patent. Patented Aug. 24, 1915.

Application filed June 1, 1914. Serial No. 842,074.

To all whom it may concern:

Be it known that I, WILLIAM F. BOCKHOFF, a citizen of the United States, residing at Richmond, in the county of Wayne 5 and State of Indiana, have invented a new and useful Sight-Feed Oiler, of which the following is a specification.

It is the object of my invention to provide a sight oil feed for attachment to machines, 10 especially in a factory, which will enable the foreman in looking over his shop to tell at a glance if any machine is not getting the proper amount of oil; and to provide an improved construction of sight oil feed for 15 forced oil lubrication systems.

In carrying out my invention, I provide two tubes one within the other, the outer one being transparent, and the inner one being perforated near the top and supplied with 20 oil at the bottom so that the oil is forced out through such perforations into the space between the two tubes, whence it passes down to the parts to be lubricated, this device being located at the top of the machine 25 so that it is readily and immediately visible by the foreman from any part of the shop in which the machine is located.

The accompanying drawings illustrate my invention. 30 Figure 1 is a sectional view showing a fragment of a machine provided with a forced oil feed and having my sight oil feed in proper position at the top; and Fig. 2 is an enlarged sectional view of the sight oil feed, *per se*.

Within the machine frame 10 is located whatever gearing 11 is necessary for the particular type of machine, this being here shown as a multiple drill. Vertically through 40 this machine extends a tube 12, which is supplied by a pipe 13 and a pump 14 with oil from a reservoir 15 at the bottom of the machine, such pump being of any desired type and shown as having a driving shaft 16 to 45 which may be clutched a driving pulley 19 normally loose on such shaft, the shaft 16 also being connected through change speed gearing 17 to the driven parts of the machine, such as the drill.

The upper end of the tube 12 is provided 50 with a stepped recess to receive a metal tube 20 and a larger transparent glass tube 21 concentric with and spaced from each other, the metal tube 20 being provided with lower 55 and upper screw threaded ends 22 and 23 the

former of which is screwed into a correspondingly threaded opening in the tube 12 so that the bores of the tubes 12 and 20 are in alinement, and the lower end of the tube 21 resting on a cork or other suitable washer 30 24. On the upper threaded end 23 of the tube 20 is screwed a cap 25, which fits over the upper end of the tube 21, a suitable cork or other washer being interposed between the cap and the end of the tube 21. The cap 65 25 is provided with a removable plug 27 at its top, this plug when removed providing an aperture for priming the pump 14. The tube 20 is provided near its upper end with a plurality of holes 28, through which oil 70 pumped by the pump 14 may escape from the tube 20 into the space 29 between the tubes 20 and 21. This space 29 extends down into the upper end of the tube 12, where it communicates with lateral passages 75 30 through such tube, the passages 30 in turn leading into a circumferential passage 31 on the tube 12, from which circumferential passage 31 any desired number of passages 32, suitably formed in the frame 10, lead to the 80 various parts to be lubricated. If the tube 12 itself serves as a bearing for gears, as in the arrangement shown, the circumferential passage 31 communicates with the bearing surface of such tube so that oil may pass 85 from such circumferential passage to such bearing surface.

In operation, the pump 14 is driven when the machine is in operation, and pumps oil 90 through the pipe 13 and tube 12 into the tube 20, whence the oil escapes through the holes 28 into the space 29, passing thence through the passages 30 to the circumferential passage 31 from which it passes either directly or by the passages 32 to the bearing 95 surfaces to be lubricated. The passage of the oil through the space 29 is visible at a glance, and in shops where there are a number of similar machines the foreman is able to tell at any time how the various machines 100 under his control are being lubricated, and can give such orders as may be necessary. In case of necessity, the pumps 14 can be primed by first removing the plugs 27. The excess of oil returns by way of the pipe 35 105 to the reservoir 15.

I claim as my invention:

1. A sight feed oiler, comprising a tube having screw threaded ends, a member in which one end of said tube is mounted, said 110

- member having an opening communicating with said tube, a transparent tube surrounding and spaced from said first tube, said member having a recess in which said transparent tube is received, and a cap which is screwed on the other end of said first tube and bears against the end of said transparent tube, said first tube having openings connecting the space between the two tubes with the space within the first tube, a removable plug in said cap for giving access to the interior of the first tube, and an oil pump for supplying oil to the opening in said member.
- 15 2. A sight feed oiler, comprising a tube having screw threaded ends, a member in which one end of said tube is mounted, said member having an opening communicating with said tube, a transparent tube surrounding and spaced from said first tube, said member having a recess in which said transparent tube is received, and a cap which is screwed on the other end of said first tube and bears against the end of said transparent tube, said first tube having openings connecting the space between the two tubes with the space within the first tube.
- 20 3. A sight feed oiler, comprising a tube, a

member in which one end of said tube is mounted, said member having an opening communicating with said tube, a cap on the other end of said tube, and a transparent tube surrounding and spaced from said first tube and clamped between said member and said cap, said first tube having an opening connecting the space between the two tubes with the space within the first tube.

4. A sight feed oiler, comprising a tube, a member in which one end of said tube is mounted, a cap on the other end of said tube, a transparent tube surrounding and spaced from said first tube and clamped between said member and said cap, said first tube having an opening connecting the space between the two tubes with the space within the first tube, and means for conducting oil to the space within the first tube.

In witness whereof, I have hereunto set my hand at Richmond, Indiana, this twenty-eighth day of May, A. D. one thousand nine hundred and fourteen.

WILLIAM F. BOCKHOFF.
